UNITED STATES PATENT OFFICE.

CROSSLEY ANDERSON MONTGOMERY BUCKLEY, OF LONDON, ENGLAND.

APPARATUS FOR PREPARING BLEACHING AND LIKE FLUIDS.

1,085,718.

Specification of Letters Patent. Patented Feb. 3, 1914.

Application filed August 13, 1913. Serial No. 784,520.

To all whom it may concern:

Be it known that I, CROSSLEY ANDERSON MONTGOMERY BUCKLEY, a citizen of the United Kingdom of Great Britain and Ireland, and resident of "Fairmount," 17 Drewstead road, Streatham Hill, London, England, have invented certain new and useful Improvements in an Apparatus for Preparing Bleaching and the like Fluids, of which the following is a specification, such as will enable others skilled in the art to which it appertains to make and use the same.

This invention relates to electrolytic apparatus for the manufacture of solution for bleaching and like purposes.

The invention consists in an improved form of such apparatus whereby a better circulation of the liquid is obtained and the apparatus can at will be used intermittently or continuously.

It is usual in constructing apparatus of this kind to employ two tanks or cisterns, or a tank divided by a partition, and to arrange the cathode in one of the tanks and the anode in the other. I adopt this construction and may make the tanks of any suitable shape but instead of simply immersing the anodes in the usual manner I place them between plates of non-conducting material in such a manner as to leave a small passage between the anodes and the plates and through which the liquid is drawn owing to the emanation of the chlorin and oxygen gases from the anodes which may be set vertically or at an angle to the vertical. If desired the upper and lower ends of the passages between the anodes and the plates are immersed in the liquid so that it is free to enter at the lower end of the passages, to travel along same and to pass out at the higher ends thereof thus forming an inflow at the lower end and an outflow at the upper end, thereby producing the desired circulation, the flow or speed of which I

may enhance by using cooling coils. The bottom of the cathode tank is so shaped that the caustic soda falling from the negative cathode can be allowed to pass completely or in part to the other tank, or may be completely shut off therefrom without interfering with the electric circulation from one tank to the other. A cooling coil, or more than one, may be employed in the cathode tank and the delivery of the caustic soda may be achieved by sloping the floor of

the cathode tank so that the caustic soda will pass from one tank to the other by gravity.

It is usual for an opening to be provided between the two tanks for the purpose *inter alia*, of maintaining the level of the liquid and I employ such an opening but preferably construct it in conjunction with a pipe or equivalent so that the opening from the cathode tank is at or toward the upper end thereof but communicates only with the lower part of the anode tank and by this arrangement I prevent, practically to an entire degree, the mixing of the solutions, the prevention of which is often very desirable if they are of different densities.

I will now describe my invention with reference to the accompanying drawings, in which:—

Figure 1 shows a tank formed in two parts *a* and *b* in the former of which the cathodes *c* are arranged while in the tank *b* the anodes *d* are placed between the plates *e* which are so positioned as to leave narrow passages *f*. The bottom of the tank *a* is sloped so as to deliver caustic soda down toward the tank *b* and such portion of it as may be desired may pass through the tap *g* into the tank *b* while if the said tap is entirely shut off the electric circuit is maintained by means of the opening *h* which communicates from the tank *a* to the tank *b* under the shield *i*. The opening *h*, in practice, should be whatever size is necessary for the electrolysis without undue resistance. Cooling coils *j* are shown in each tank and taps 1, 2, 3 are provided to permit of continuous supply, continuous drawing off of bleaching solution and for draining purposes respectively.

In Fig. 2 the general arrangement is much the same as that in Fig. 1 and like reference letters are employed but the anodes and their dividing plates are arranged vertically and the cooling coils are of a different form.

In Fig. 3 two tanks *a* and *b* are again employed and the arrangement of the anodes *d* and their plates *e* are substantially as shown in Fig. 1. In this example the bottom of the tank *a* is tapered or cone-shaped and the cathode *c* with the coil *j* is adapted to be moved from one side of the tank to the other so that the caustic soda formed in the tank will be deposited either on the left hand side so as to be entirely shut off from possibility of passing to the tank *b* and may

be drawn off by the tap 4, or, if the cathode is moved to the right hand side of the tank and the three-way cock 5 is opened, the caustic soda can pass from the tank *a* to the tank *b*. The bent pipe *k* serves to maintain the necessary connection between the two tanks as do the opening *h* and the plate *i* in Fig. 1, the connection being between the top of the cathode tank and the bottom of the anode tank.

It will be seen from each of these drawings that the cooling coils are so positioned as to receive the heated solution and by cooling it to promote the desired circulation.

The anodes with their plates are preferably constructed so as to be moved, withdrawn and replaced *en bloc* as is also the cathode and coil shown in Fig. 3.

The operations of the apparatus will be apparent to any person conversant with the manufacture of bleaching solution by electrolytic apparatus who will observe that the hydrogen gas from the cathode cannot possibly enter the tank in which the anodes are arranged but will pass upwardly and escape into the atmosphere while the caustic soda formed in the same tank will, when required, pass into the anode tank and because of the circulation of the liquid therein will be diffused around the lower ends of the anodes and drawn upwardly between them and the deflecting plates, while the level of the liquid is maintained by means of the opening *h* or the pipe *k*.

When the bleaching solution in the anode tank is of required strength the electric current is shut off and the tap *g* or 5 as the case may be, is shut off so that the liquid in the anode tank can be drawn away and used as required.

Should the solution required be such that caustic soda is not found to be desirable during the operation of electrolysis as when the solution in the anode tank is to be used in bleaching substances such as oils and fats the entry of caustic soda to the anode tank is prevented as by closing the cock between the tanks or having the cathode as shown in Fig. 3.

What I claim and desire to secure by Letters Patent is:—

1. Apparatus for preparing bleaching and the like fluids comprising two connected tanks with a plurality of anodes in one tank and a cathode in the other tank with non-conducting plates between the anodes.

2. Apparatus for preparing bleaching and the like fluids comprising two connected tanks with a plurality of anodes set at an angle to the vertical in one tank and a cathode in the other tank with non-conducting plates between the anodes, said plates being parallel to the anodes.

3. Apparatus for preparing bleaching and the like fluids comprising two connected tanks in one of which anodes are arranged and are separated by non-conducting plates and in the other of which tanks the cathode is arranged with a connection and valve between the tanks so arranged that the quantity of caustic soda passing from the cathode tank to the anode tank can be regulated or can be entirely shut off.

4. Apparatus for preparing bleaching and the like fluids comprising two tanks and an anode in one tank and a cathode in the other tank, cooling coils in the anode tank, means for permitting and regulating the flow of caustic soda from the cathode tank to the anode tank, means for maintaining the level of fluid in the two tanks and means for drawing off the prepared solution and means for maintaining the supply of solution to the cathode tank.

5. Apparatus for preparing bleaching and the like fluids comprising two tanks in one of which the anode is arranged and in the other of which the cathode is arranged with a connection and valve or equivalent between the two and so arranged that the quantity of caustic soda passing from the cathode tank to the anode tank is controlled by making the bottom of the cathode tank of tapered or cone shape and in such relation to the cathode that the caustic soda can at will be shut off from passing to the anode tank or can be directed toward same.

6. Apparatus for preparing bleaching solution comprising two adjacent connected tanks one of which has a cone-shaped bottom and has in it cathodes, the other tank being of any suitable shape and having in it anodes with means for moving the cathodes in relation to the bottom of the tank in which they are placed.

In witness whereof I have hereunto set my hand in presence of two witnesses.

CROSSLEY ANDERSON MONTGOMERY BUCKLEY.
